H. J. C. WELLS

THERMOSTATIC REGULATOR

Filed Dec. 27, 1921

FIG. 2.

FIG. 3.

INVENTOR
Herbert J. C. Wells,

BY
_____
ATTORNEYS.

UNITED STATES PATENT OFFICE.

HERBERT JAMES CLEMENT WELLS, OF NEW YORK, N. Y.

THERMOSTATIC REGULATOR.

Application filed December 27, 1921. Serial No. 524,853.

To all whom it may concern:

Be it known that I, HERBERT J. C. WELLS, a subject of the King of Great Britain, residing at New York, N. Y., have invented 5 a new and useful Thermostatic Regulator, of which the following is a specification.

My present invention has two main objects, namely, to provide a simple, inexpensive safety relief element for a thermostatic 10 device of the type set forth in my Patent No. 1,392,031, and to utilize certain principles of the invention of said patent in a saturated vapor type of regulator.

Another object is to apply the principle 15 of the improved safety relief device in a simple manner to a saturated vapor type of regulator.

In the accompanying drawings I have shown three modifications of my invention, 20 but it should be understood that I contemplate that other variations and modifications may be made within the scope of my invention.

Figure 1 is a more or less diagrammatic 25 side view and partial section of apparatus embodying one form of my invention; and

Figs. 2 and 3 are partial side views and sections of other forms of thermostatic devices embodying certain features of my im- 30 provements.

The fluid or medium to be controlled passes through the conduit or pipe 5. Interposed in this conduit is a section 6 of relatively thin metal of high specific thermal 35 conductivity. Surrounding this section 6 is a casing 7, spaced apart from it, so as to form a chamber 8 for the controlling fluid, the rise and fall of the volume of pressure of which is to be used in operating some 40 form of control valve 9.

In the form shown in Fig. 1 I employ an expansible chamber 10 in the form of metallic bellows or diaphragm, the movable part of which is connected to the valve. The 45 chamber of this expansible element is connected by a small tube 11 to the bottom of the chamber 8. This arrangement is intended to employ a highly volatile liquid, such as ether, and the valve is operated by 50 changes in tension of the saturated vapor.

The temperature at which the valve is operated is controlled by the setting of the adjustable weight 12, as is common in mechanism of this general type.

55 In apparatus of this saturated vapor type

of control it has always been customary, so far as I know, heretofore to employ some form of bulb containing highly volatile liquid, and to immerse this bulb in the vessel containing the fluid to be controlled. 60 I have found that by employing a thermostatic device such as herein described a much more sensitive action is obtained without any additional expense or complicated mechanism or method of installation. By 65 disposing the expansion agent in the form of a thin film or layer about the heat absorption surface I obtain a maximum sensitivity. Changes in temperature of the fluid passing through the conduit 5 are almost instantly communicated to the volatile liquid in the chamber 8, and the change in vapor tension immediately affects the expansible device 10 in the valve 9. The double wall tubing may be straight, as here- 70 in shown, or coiled or bent so as to bring it into any desired shape or limited space.

In a system of this type excessive pressure tends to condense the vapor and relieve the pressure. As an additional precaution, 80 I propose to provide, if necessary, an expansible coil, preferably of oval or elliptical cross section which tends to act like a Bourdon tube and expand with increases in pressure. This relief tube is preferably connected direct to the fluid chamber 8, and may be in the form of a coil 13 surrounding the casing 7 and forming a part of the conduit which connects the chamber 8 with the expansible member 10. One end of this 90 coil 13 is secured to the casing 7, and the other end is free to move as the coil expands and contracts. To facilitate the movement I may also provide another coil 14 in the conduit, though there will be no tendency 95 to restrict or retard the expansion and contraction of the coil 13. When the pressure in the chamber 8 becomes excessive, the coil 13 will tend to straighten out and increase in volume, and thus avoid the effect of pressure, which might otherwise be destructive.

The relief coil may be independent of the conduit which connects the thermostatic element to the valve operator, as indicated in Figs. 2 and 3. It should also be understood 105 that the principle of this relief element may be employed with valve operating mechanism of the form shown in my former patent, and also that the relief element is adapted to thermostatic devices employing relatively 110

nen-volatile liquids. The conduit 15 in Figs. 2 and 3 is intended to represent a connection to any form of valve mechanism.

In the form shown in Fig. 3, the relief 5 coil 16 is mounted within the fluid chamber 8 and is open at 17 to atmospheric pressure. In this case both ends of the coil 16 are free to move, and its central portion is connected to the casing 7. Increase in pressure 10 in the chamber 8 tends, of course, to contract the coil 16 and thus relieve excessive pressure.

In the form shown in Fig. 2 the relief coil 18 is connected to the outside of the 15 casing 7, independently of the conduit 15, which leads to the valve operating mechanism, and in this case relief of excessive pressure is afforded by expansion of the coil 18.

20 I claim:

1. In a thermostatic regulator, a conduit for the fluid whose temperature is to be controlled, said conduit having a section formed of a relatively thin wall of metal of 25 high specific thermal conductivity, a casing surrounding said section but spaced apart therefrom to provide a chamber for a regulating fluid, and a relief coil having one end stationary and another end freely movable 30 and subjected to the pressure within said chamber.

2. In a thermostatic regulator, a casing having an inner wall of high thermal conductivity through which the fluid to be regulated 35 flows, and having an outer wall spaced apart from the inner wall to form a chamber adapted to contain a fluid, and a relief tube having one end secured to one of said walls and coiled about the same.

40 3. In a thermostatic device, a conduit having an inner wall of high specific thermal conductivity, and an outer wall spaced apart therefrom and forming a chamber surrounding the inner wall, and a relief tube connected to said outer wall and coiled about the same.

4. In a thermostatic regulator a conduit for the fluid to be controlled having a section of a relatively thin wall of high specific thermal conductivity, a casing surrounding 50 said section but spaced a small distance therefrom to provide a thin chamber for a regulating fluid, a control valve and expandable member operating said valve, a tube of small diameter connecting the lower part of 55 said chamber and said expandable member, a highly volatile liquid partially filling the space within said chamber, said tube and said member, whereby the pressure developed in said chamber is communicated to 60 said expandable member, and adjustable means for varying the initial pressure within said expandable member to thereby select the temperature at which the apparatus will operate.

5. In a thermostatic regulator, a conduit for the fluid to be controlled, a casing surrounding a part of said conduit and forming a chamber partially filled with a vaporizable liquid, a valve, an expandable member for 70 controlling said valve, and a tube connecting said expandable member with said chamber, said tube having an expandable section.

6. In a thermostatic regulator, a conduit, 75 a casing surrounding the conduit and forming a chamber for a vaporizable liquid, a valve, an expandable member for operating said valve, and a tube connected to said casing and coiled about the same and connected to said expandable member.

80 7. In a thermostatic device, a conduit for fluid to be controlled, a chamber in contact with a wall of said conduit and containing a fluid sensitive to temperature changes in said conduit, and a relief tube of oval cross 85 section having one end anchored to said chamber and the other end movable, said tube being exposed to the pressure within said chamber on one side and to atmospheric pressure on the opposite side.

HERBERT JAMES CLEMENT WELLS.
